UNITED STATES PATENT OFFICE.

JESSE N. ROBERTSON, OF PORTLAND, OREGON.

SHOE CLEANER AND SCRAPER.

Application filed May 10, 1921. Serial No. 468,209.

To all whom it may concern:

Be it known that JESSE N. ROBERTSON, a citizen of the United States, residing at Portland, in the county of Multnomah and 5 State of Oregon, has invented certain new and useful Improvements in Shoe Cleaners and Scrapers, of which the following is a specification, reference being had therein to the accompanying drawing.

10 The invention relates to combined shoe cleaners and scrapers and has for its object to provide a device of this character comprising a casing formed from registering sections in which casing is disposed horizontally 15 disposed shafts in axial alignment with each other and provided with heads adjacent each other between which heads and the ends of chambers in which the heads are disposed, coiled springs are disposed and 20 forming means for normally holding said heads inwardly. The ends of said axially disposed shafts extend inwardly and terminate in horizontally disposed portions in parallel relation to the 25 shafts within the casing and adjacent a shoe scraping rib formed by the flanges of the casing sections. Also to provide the horizontally disposed portions with shoe cleaning brushes, which brushes are slidably 30 mounted on the shoe scraping rib of the casing.

A further object is to provide means whereby the brushes may be adjusted in relation to each other and limited in their inward movement.

With the above and other objects in view the invention resides in the combination and arrangement of parts as hereinafter set forth, shown in the drawings, described and 40 claimed, it being understood that changes in the precise embodiment of the invention may be made within the scope of what is claimed without departing from the spirit of the invention.

45 In the drawings:—

Figure 1 is a perspective view of the shoe cleaner and scraper.

Figure 2 is a vertical longitudinal sectional view through the cleaner and scraper.

50 Figure 3 is a vertical transverse sectional view taken on line 3—3 of Figure 1.

Referring to the drawings, the numeral 1 designates a casing, which casing is formed from similarly shaped sections 2, and 3,

55 which sections may be stamped from sheet metal or cast if so desired. However the

sections are preferably similarly shaped so that they are interchangeable and in manufacture and assembly would materially reduce the cost. The casing sections 2 and 3 are provided with longitudinally disposed semi-circular chambers 4, which chambers when brought together form a horizontally and longitudinally disposed chamber 5. The lower edges of the portions of the sections 60 2 and 3, that is their semi-circular sections have downwardly extending flanges 6 which are adapted to be secured together by means of screws 7, said flanges 6 terminating in outwardly extending base members 8 which 65 may be secured in any suitable manner to a support. Extending upwardly from the upper sides of the sections 2 and 3 are registering flanges 9, which flanges form a scraper for scraping mud from the sole of the shoe 70 when the operator's foot is forced between the shoe cleaning brushes 10. The shoe cleaning brushes 10 are provided with recesses 11 in their under sides, which recesses receive the scraper flanges 9, and on which 75 scraper flanges the brushes slide and are guided during a shoe cleaning operation when the operator's foot is moved inwardly and outwardly between the brushes.

Disposed within the chamber 5 are the 80 lower horizontally disposed arms 12 of U-shaped members 13, said arms 12 being preferably in axial alignment as clearly shown in Figure 2. The arms 14 of the U-shaped members 13 extend inwardly from the vertical portions 15 of said members, and have their ends secured as at 16 to the brushes 10, arms 14 being spaced from the upper edges of the scraper flanges 9 so as not to contact with the same during the reciprocation of the brushes 10 on said flanges. Secured to the inner ends of the shafts 12 are headed members 17 and between which headed members and the closed ends 18 of the semi-circular chambers 4, coiled springs 19 are interposed, said coiled springs forming means for normally forcing the heads 17 toward each other and consequently maintaining the brushes 10 at their inward position as shown in Figure 2, thereby during 105 a shoe cleaning operation when the operator forces the shoe between the brushes, said springs will act to maintain the brushes in contact with the shoe during the movement of the shoe between the brushes.

110 The brushes may be adjusted in relation to each other, that is so that their inward

movement may be limited to a predetermined point by means of adjustable collars 20 disposed on the arms 12, and which collars may be adjusted to engage the closed 5 ends 18 and limit the inward movement of the arms 12.

It will be seen that a combined shoe cleaner and scraper is provided which is simple in construction and one wherein the 10 brushes are slideable and guidable on the scraping element and carried by arms of U-shaped members, thereby forming the U-shaped members of material with slight flexibility, the brushes will be prevented from 15 sticking or jamming on the scraping flanges 9. It will also be seen that as the shoe of the operator is forced inwardly and outwardly between the brushes 10, that said brushes by being slideably mounted on the 20 flanges 9 will not throw the main strain on the arms 14 of the U-shaped members, said strain being taken up by the flanges 9.

The invention having been set forth what is claimed as new and useful is:—

25 1. A shoe cleaning device comprising a cylindrical casing having a cylindrical chamber therein and closed end walls, U-shaped members having their arms extending towards each other in axial alignment, the arms of each U-shaped member being in parallel relation, said U-shaped members being formed from rod material, the lower arms being axially disposed within the cylindrical chamber of the casing, and extending 30 through apertures in the end walls thereof, a longitudinally disposed rib carried by the upper side of the casing, brushes carried by the ends of the upper arms and slideably

40 mounted on the rib, heads carried by the inner ends of the lower arms and slideably mounted in the chamber of the casing, and coiled springs interposed between said heads and the end walls of the casing.

45 2. The combination with a shoe cleaning device comprising a casing, U-shaped members formed from rod material and having their arms extending towards each other in axial alignment, a longitudinally disposed rib carried by the casing, brushes carried by the upper arms and slideably mounted on the 50 rib, the lower arms extending through apertures in the ends of the casing, spring means for normally forcing said lower arms inwardly, and an adjustable stop carried by the lower arms and cooperating with the 55 ends of the casing and limiting the inward movement of the arms.

60 3. A shoe cleaning device comprising a casing, a longitudinally disposed rib carried by said casing, brushes slideably mounted on said rib, U-shaped members formed from rod material and having their arms extending toward each other and in axial alignment with each other, the upper arms of said U-shaped members being connected to the brushes, the lower arms of the U-shaped members being slideably mounted in the casing, springs surrounding said lower arms and cooperating therewith for holding the same in inward position, and adjustable stops carried by the 65 lower arms of said U-shaped members and cooperating with the casing whereby the inward movement thereof may be limited.

70 In testimony whereof I hereunto affix my signature.

JESSE N. ROBERTSON.
